MARIA FELDMAN, OF NEW YORK, N. Y.

BUST SUPPORTER AND REDUCER.

1,060,329.

Specification of Letters Patent. Patented Apr. 29, 1913.

Application filed June 29, 1909. Serial No. 504,983.

To all whom it may concern:

Be it known that I, MARIA FELDMAN, a citizen of the United States, residing in the borough of Manhattan, in the city of New York, county and State of New York, have invented certain new and useful Improvements in Bust Supporters and Reducers, of which the following is a full, clear, and exact specification.

10 This invention relates to bust supporters and reducers and has for its object, primarily, the supporting and the reducing of the bust of women and the rejuvenating of their forms, especially women who have large 15 busts and are corpulent.

15 The corsets that are in general use at the present time are commonly made of two parts or sections and when applied to the bodies of stout women have a tendency to 20 force the surplus flesh and also the busts up toward the neck and thereby causing this part of the body to be unsightly as well as uncomfortable to the wearer of the corset, and the positioning of the busts higher than is 25 natural. I aim to remedy this defect by so constructing my improved bust supporter and reducer that the bust will be placed in its proper position giving the wearer a younger appearance in addition to comfort, 30 the latter being insured by the depressing of the surplus flesh or corpulency which is formed around the neck, under the arms, and on the back, the supporter operating to reduce this flesh and bring the bust to the 35 symmetrical form.

Reference is to be had to the accompanying drawings forming a part of this specification, in which similar characters of reference indicate corresponding parts in all the 40 figures.

Figure 1 is a front view of a figure having a bust supporter and reducer applied thereto embodying my invention. Fig. 2 is a back view of the same, and Fig. 3 is a 45 side view of the same.

My bust supporter and reducer is made up of three sections, the same comprising two front sections 5, 5, and a combined rear and side section 6, the two front sections being 50 practically the same except that one is a right section, and the other a left section, and are detachably connected together at the adjoining edges by means of hooks and eyes or other suitable fastenings common to corsets. 55 Each front section at its outer edge is provided with a row of eyelets 7 and at inter-

mediate points with pockets 8 and 9, the pocket 8 arranged approximately parallel to the outer edge of the section, and the pocket 9 arranged parallel to the inner edge 60 of the section and joining the pocket 8 at the bottom, each pocket containing a whalebone with the whalebone in the pocket 9 extending from the bottom of the section to a point about midway of its length. The 65 combined side and back section of the bust supporter and reducer is constructed of three pieces of suitable fabric, comprising two front side pieces or sections 10, 10, two rear side pieces or sections 11, 11, and a back 70 piece or section 12, the latter being gored and secured at the edges to the rear side pieces 11 which in turn are secured at the opposite edges to the front side pieces 10. The front edges of the front side pieces 10 75 are concave to conform to the convexity of the outer side edges of the front section and are each provided with a row of eyelets 13 matching with the eyelets 7 from which they are separated a substantial distance and 80 are connected by laces 14. These laces are started at each side of the transverse center of the garment and are tied adjacent to the upper and lower edges. The front sections 85 of the supporter and reducer are further connected to the front pieces 10 of the combined side and back section by straps 15, two of these straps being shown at each side of the garment arranged between the two laces.

The back piece 6 at each side and each 90 front side piece 10 have a half portion of a shoulder strap 16 with one of said portions provided with a tongue 17 arranged to extend under the other portion and the two 95 portions detachably connected together by a lace 18.

The back piece 6 is made of two sections which are sewed together at the center to form a stiffening rib 19 the same serving to make the garment conform to the body. 100 The front side pieces 10 have pockets arranged substantially parallel and adjacent to their eyelet edges in which whalebones 20 are contained, the same serving to stiffen the garment along these lines.

105 The warp of the fabric of which the front sections of the garment and the front side pieces and back piece of the garment is made extend transversely of the body and the warp of the fabric of the rear side pieces extends longitudinally of the garment. Thus 110 the sections or pieces 11 have slight elastic-

A NEW AND USEFUL INVENTION

ity transversely and allow the garment to expand within the limits which they afford in breathing and under the tension of the straps and lacings, whereas, the remaining sections or pieces of the garment are inelastic in a like direction, but have the same elasticity lengthwise of the body and adapted to stretch over the bust and back. This construction of the supporter when the same is applied to stout people tends to cause the woven fabric to seize and draw down the surplus flesh around the neck and shoulders giving the bust a rounder form and a juvenile appearance, and prevents the formation of rolls of flesh over the top edge of the tightly-drawn corset.

The lacing of the garment together at the shoulders enables the wearer to so adjust the garment sections as to bring the bust to proper position, and the adjustment afforded by the laces and straps at the front adapts the supporter sections to be drawn together at both the top and bottom so as to give the bust a rounding symmetrical form without discomfort to the wearer. The straps allow the garment to be adjusted in a general way to the figure preparatory to the adjustment of the lacings. The straps also take a considerable portion of the strain between the front sections and the front side sections of the garment. The open space between each pair of straps is suitable for mothers with nursing children without the inconvenience of having to open the corset in the customary way.

Adjustment of the bust of the wearer either up or down may be effected by manipulation of the upper and lower laces 14. If it is desired to lower the bust, the upper laces are first tightened, to cause the upper portion of the bust-adjusting section 5 to

compress or push the bust downwardly; and then the lower laces 14 are made moderately tight. If it is desired to adjust the bust upwardly, the lower laces 14 are first tightened, causing the lower part of the bust-adjusting section 5 to tighten and lift up the bust; whereupon the upper laces 14 are made moderately tight.

Having thus described my invention, I claim as new and desire to secure by Letters Patent—

A body-supporting and flesh-reducing corset formed to end above the hips and having arm-holes and comprising side sections of woven material extending down from the arm-holes, the warp threads thereof extending vertically whereby said side sections are stretchable in a direction about the body of the wearer to fit the corset snugly thereto, back sections intervening between said side sections and continuing in the form of bands up over the shoulder, and front sections between said side sections, certain of said front sections extending up over the shoulder and laced to the tops of said back sections, the latter and certain of the front sections being of woven material and all with the warp threads extending longitudinally whereby said front sections are stretchable in up and down direction and have moderate elasticity and are tensioned between the shoulder lacings and the bottom portion of the front lacings, to exert a downward pull upon the flesh of the wearer, to prevent formation of rolls of flesh over the top of the corset.
